VAPOR EMANATOR

Russell B. Kingman, Orange, N. J., assignor to
Housekeeping Products Co., East Orange, N. J.,
a corporation of New Jersey

Application December 15, 1938, Serial No. 245,821

10 Claims. (Cl. 219—45)

This invention relates to an improved form of vapor emanator for vaporizing a suitable agent or substance with the air of applied heat and disseminating the emitted vapor or fumes to thereby deodorize, disinfect or perfume the surrounding air; and the invention has reference, more particularly, to a novel construction of emanator adapted for application to either an upstanding or pendant electric light bulb so as to be supported thereby and so as to utilize the radiant heat thereof in aid of the operative vaporizing and disseminating processes.

This invention has for an object to provide a vapor emanator of the kind and for the purposes mentioned comprising, a chambered member of annular form provided with vapor vents, said member being charged with a vaporizable agent or substance capable of emanating vapors or fumes of desired character, together with means for operatively relating said member in attached supported relation to an electric light bulb in such manner that warm air in the vicinity of the lighted bulb is so controlled as to be caused to move in ascending streams adjacent to the vapor vents to thereby assure a rapid and efficient dissemination and diffusion to the surrounding atmosphere of the vapors or fumes emitted from said vents.

The invention has for another object to provide a vapor emanator characterized as above stated, wherein the body of the annular chambered member constituting the same is provided with air admission means to receive, for passage through the body interior, a portion of the warm air in the vicinity of the lighted bulb to which the body is applied, whereby not only is the vaporizing of the contained agent or substance assisted and hastened, but the emission of the resultant vapors and fumes is also expedited.

Other objects of this invention, not at this time more particularly enumerated, will be understood from the following detailed description of the same.

Illustrative embodiments of this invention are shown in the accompanying drawings, in which:

Fig. 1 is an elevational view of one form of the novel vapor emanator according to this invention as operatively applied to an upstanding electric light bulb; Fig. 2 is a similar view showing the emanator operatively applied to a pendant electric light bulb; Fig. 3 is a top plan view of the emanator per se; Fig. 4 is a bottom plan view of the same; and Fig. 5 is a vertical cross-sectional view of the same, drawn on a somewhat enlarged scale.

Fig. 6 is a vertical cross-sectional view of a somewhat modified form of the novel vapor emanator operatively applied to an upstanding electric light bulb; and Fig. 7 is a bottom plan view of this emanator per se.

Fig. 8 is a vertical cross-sectional view of another modified form of the novel vapor emanator operatively applied to a pendant electric light bulb.

Fig. 9 is a top plan view, and Fig. 10 is a vertical cross-sectional view of still another modified form of the novel vapor emanator.

Similar characters of reference are employed in the hereinabove described views, to indicate corresponding parts.

Referring to Figs. 1 to 5 of the drawings, one embodiment of the vapor emanator according to this invention, as therein shown, comprises an annular bottom section 11 of U-shape or other selected cross-sectional shape, the same providing an interior chamber 12 open at its top side. Cooperative with the open top side of said bottom section 11 is a top section or cover 13, preferably adapted to telescope thereover to close the open top of said interior chamber 12. Said top section or cover 13 is preferably of upwardly arched cross-sectional shape, and formed therein, between the annular central axis thereof and its inner margin or periphery is an annular row of spaced perforations which serve as vapor vents 14 leading outwardly from the interior chamber 12, and, by reason of their described disposition, directed inwardly toward the surface of an electric light bulb B when applied in operative assembled and supported relation to the latter.

Formed in connection with the inner wall of said bottom section 11, adjacent to the upper margin thereof, are a plurality of outwardly pressed hollow bosses or ribs 15 open toward the interior chamber 12. Said bosses or ribs 15 are thus circumferentially spaced around the inner side emanator, so as to provide intervening gaps or passageways 16. The under sides of said bosses or ribs 15 are placed to provide air intake openings 17, in such manner that the upper sides of said bosses or ribs overhang these openings so as to provide deflector sections 18 which deflect or turn upwardly moving air into the interior chamber 12 of the emanator.

The bottom of said interior chamber 12 provides a basin 19 within which is deposited an agent or substance 20 of suitable character capable, when evaporated, to emit vapors or fumes for desired effects of deodorization, disin-

fection or perfuming of the surrounding air into which they are emitted and disseminated.

The agent or substance 20 may be furnished in any suitable form, i. e. of either liquid, solid, powdered, or pastry form. For example, a volatile substance capable of yielding vapors or fumes, adapted to permeate the atmosphere for a desired effect, may be mixed with or incorporated in paraffin, a low melting point solid, so that when 10 the latter is cool and solidified, said substance is imprisoned therein with tendency to suppress evaporation thereof when functional operation of the emanator is not desired; but, when heat is applied sufficient to melt the paraffin, said 15 substance will be liberated and readily evaporated. Such combination of low melting point carrier and a selected volatile active substance has the advantage that, when cool and solidified, it will not spill, and consequently the emanator 20 charged with the same can be more conveniently handled both during commercial distribution and by the ultimate user. While such combination is perhaps preferred for the reasons given, I do not limit myself solely thereto, since so far as 25 the novel structure of the emanator as a container is concerned, it is indifferent to the particular form or kind of volatile substance employed, or to the condition of said substance used either alone or in combination with a suitable carrier or vehicle.

The internal diameter of the annular emanator device is somewhat less than the maximum external diameter of an electric light bulb B with which it is to be operatively associated. The 30 emanator device is provided with resilient retainer member which may be utilized to hold the device against displacement when applied upon the top end portion of an electric light bulb B disposed in an upstanding position. In a preferred form and arrangement thereof, said retainer members comprise a pair of circular loop members 21 made of spring wire, the same being respectively anchored or affixed to diametrically opposite points at the exterior underside of the 35 bottom section 11, and so as to fold flatly against the latter when not in use (see Fig. 4). When desired to be used, the free sides of the loop members 21 are flexed to turn the same downward so as to permit the bulb B to pass upward there- 40 between until the emanator device seats itself on the bulb top, whereupon, when said loop members 21 are released the same spring inwardly toward and around the bulb sides so as to grip the bulb, and thus anchor the emanator device 45 thereon (see Fig. 1). If the emanator device is applied to a pendant bulb, the retainer loop members 21 need not be used, but remain folded against the underside of the bottom section thereof (see Fig. 2).

60 When the emanator device is adapted to the electric light bulb B, the bosses or ribs 15 contact the bulb sides so as to space the inner wall of the bottom section therefrom. Inasmuch as there are gaps 16 between adjacent bosses or ribs 65 15, free or open air passageways are provided intermediate the emanator device and the bulb. When the bulb is lit, the air surrounding the same will be heated by heat radiated from the bulb, and being lighter will naturally tend to rise, 70 and consequently convection air currents will be caused to flow upwardly through said gaps 16. The heat radiated from the lighted bulb also applies itself to the emanator device and its vaporizable content, so that the desired vapors or fumes are liberated. By reason of the provision

of the air intake openings 17 formed in the undersides of the ribs or bosses 15, and which co-operate with the overhanging deflector sections 18, a proportion of the rising heated air will be caused to enter the interior chamber 12 of the emanator device, and by its movement and pressure therein will not only assist in the vaporizing effects upon the substance 20, but will set up a circulation or draught through the interior chamber 12 which will efficiently carry the liberated vapors or fumes outwardly through the vents 14 to join the rising air streams flowing upwardly through the passageways 16 and thus to be carried quickly away from the bulb and disseminated in the surrounding atmosphere. It will be noted that the vents 14 are so located at the sloping inner area of the top section or cover 13 that the vapors or fumes emitted therethrough are directed definitely toward the rising air streams so as to be readily mingled therewith and carried away thereby.

In Figs. 6, 7 and 8 there is shown a somewhat modified construction of the novel emanator device according to this invention, the same comprising an annular bottom section 30 of suitable cross-sectional shape and provided with a closing top section or cover 31 having vapor or fume vents 32 leading from the interior chamber 33. Pressed out from the inner walls of said bottom section are ribs or bosses 34 to engage the sides of a bulb B to which the device is operatively applied, and so as to produce intermediate passages for the upward flow of air as above referred to. The means to introduce a portion of ascending air into and for circulation through the chamber 33 and its vents 32, is of somewhat different form, and comprises tubular ducts 35 affixed to the bottom of the section 30 to extend upwardly through the interior thereof and its content of vaporizable substance 20 to the space 40 above the level of the latter, thus conducting warm air, the heat of which may be radiated from the duct walls directly to the substance 20, while at the same time the circulation of the currents of air through the interior aids in carrying 45 away liberated vapors or fumes through the vents 32 to join the external air streams for dissemination therewith to the surrounding atmosphere. Said ducts 35 may be optionally disposed so as to incline their receiving ends toward the bulb sides, 50 as shown in Figs. 6 and 7, or so as to incline their discharge ends toward the vents 32, as shown in Fig. 8. If desired, a plurality of radial and inwardly extending resilient bulb gripping arms or members 36 may be affixed to the emanator device, as shown in Figs. 6 and 7, in place of the resilient loop members previously described.

In Figs. 9 and 10 there is shown a simpler form of the emanator device of this invention, which, however, still embodies certain of the novel principles of this invention. In this simple form thereof, the device comprises an integral annular body 40 suitably shaped to provide a trough-like bottom section 41 and inner and outer top sections 42 and 43, so formed and related that the free marginal portion of the outer section 43 is spaced from and somewhat overhangs the free marginal portion of the inner section 42, thus providing an annular inwardly described vent mouth 44 which is directed toward the sides of a 70 bulb to which the device is applied in use. Pressed out from the inner side of the body 40 are circumferentially spaced ribs or bosses 45 providing intermediate air passages 46 to serve the purposes already above described.

In all of the above described constructions, the 5
projectional extent of the bulb contacting ribs or
bosses may be selected or predetermined so as to
dispose the body of the emanator nearer to or
farther from the sides of the bulb according to
the desire to increase or diminish the effects of
heat radiated from the bulb in aid of evaporation
10 of the content of the device. Ordinarily the
closer the emanator body is disposed relative to
the bulb, the greater the effective heat and more
rapid the evaporation, but if the emanator body
is further removed from the bulb sides, the less
15 effective is the heat and the slower the evapo-
ration.

15 It may also be pointed out that in order to
assist in stabilizing the attached relation of the
emanator device to the bulb, the bulb contacting
ribs or bosses of the former may be coated with
20 a tacky more or less adhesive substance, such
e. g. as latex, rubber or other suitable gum,
which will afford a non-slipping contact with the
glass of the bulb.

Although the invention has been described in
25 detail, it is not to be limited to the exact con-
struction as shown, since variations may be
made within the spirit of this invention and the
scope of the here following claims.

I claim:

30 1. A vapor emanator comprising, a hollow an-
nular body to contain a vaporizable fume emit-
ting substance and adapted to be supported by
and around an electric light bulb, said body
having spaced means to abut the bulb sides
35 disposed to project from the inner walls thereof,
thereby providing air flow passages intermediate
the same and said bulb, and said body having a
closed top portion provided with vent means lead-
ing from the body interior and directed toward
40 the sides of the bulb to which said body is applied
to discharge emitted fumes into the air streams
flowing upwardly through said air flow passages
intermediate said body and bulb.

2. A vapor emanator comprising, a hollow an-
nular body to contain a vaporizable fume emit-
ting substance and adapted to be supported by
45 and around an electric light bulb, said body hav-
ing spaced means to abut the bulb sides dis-
posed to project from the inner walls thereof,
thereby providing air flow passages intermediate
50 the same and said bulb, said body having a closed
top portion provided with vent means extending
around the same to lead from the body inter-
ior and directed toward the sides of the bulb
55 to which the body is applied to discharge emitted
fumes into the air streams flowing upwardly
through said air flow passages, intermediate said
body and bulb, and resilient retainer means con-
60 nected with the bottom portion of said body
adapted to embracingly engage said bulb to hold
65 said body against displacement therefrom.

3. A vapor emanator comprising, a hollow an-
nular body to contain a vaporizable fume emit-
ting substance and adapted to be supported by
65 and around an electric light bulb, said body
having spaced means to abut the bulb sides dis-
posed to project from the inner walls thereof,
thereby providing air flow passages intermediate
70 the same and said bulb, said body having in its
top portion upwardly and inwardly directed vent
means to discharge emitted fumes into the air
streams flowing upwardly through said passages,
resilient retainer means connected with the bot-
75 tom portion of said body adapted to embracingly
engage said bulb to hold said body against dis-
placement therefrom, said retainer means com-

prising a pair of circular spring wire loop mem-
bers respectively affixed to diametrically opposite
points of said body bottom portion to normally
lie flatly folded thereagainst but capable of being
flexed and spread apart to receive said bulb 5
therebetween.

4. A vapor emanator comprising, a hollow an-
nular body to contain a vaporizable fume emit-
ting substance and adapted to be supported by
and around an electric light bulb, said body 10
having spaced means to abut the bulb sides
disposed to project from the inner walls thereof,
thereby providing air flow passages intermediate
the same and said bulb, said body having a
closed top portion provided with vent means ex-
15 tends around the same to lead from the body
interior and directed toward the sides of the
bulb to which the body is applied to discharge
emitted fumes into the air streams flowing up-
wardly through said air flow passages interme-
20 diate said body and bulb, and said body also
having air admission means leading upwardly
into and communicating with the interior there-
of above the level of fume emitting substance
25 contained therein whereby a draught is induced
through said body interior to both enhance
vaporization of the substance contained in said
body and to aid in discharging the resultant
fumes through said vent means.

5. A vapor emanator comprising, a hollow an-
nular body to contain a vaporizable fume emit-
ting substance and adapted to be supported by
and around an electric light bulb, said body
having spaced means to abut the bulb sides dis-
35 posed to project from the inner walls thereof,
thereby providing air flow passages intermediate
the same and said bulb, said body having a
closed top portion provided with vent means
extending around the same to lead from the
40 body interior and directed toward the sides of 40
the bulb to which the body is applied to dis-
charge emitted fumes into the air streams flow-
ing upwardly through said air flow passages in-
termediate said body and bulb, said body also
45 having air admission means leading upwardly 45
into and communicating with the interior there-
of above the level of fume emitting substance
contained therein whereby a draught is induced
through said body interior to both enhance
50 vaporization of the substance contained in said
body and to aid in discharging the resultant
fumes through said vent means, and resilient
retainer means connected with the bottom por-
55 tion of said body adapted to embracingly engage
said bulb to hold said body against displacement
therefrom.

6. A vapor emanator comprising, a hollow an-
nular body to contain a vaporizable fume emit-
ting substance and adapted to be supported by
60 and around an electric light bulb, said body hav-
ing spaced means to abut the bulb sides disposed
to project from the inner walls thereof, thereby
providing air flow passages intermediate the same
and said bulb, said body having in its top portion
65 upwardly and inwardly directed vent means to
discharge emitted fumes into the air streams
flowing upwardly through said passages, said
body also having air admission means leading
upwardly into the interior thereof whereby a
70 draught therethrough is discharged through said
vent means to both enhance vaporization of the
substance contained in said body and to aid in
discharging the resultant fumes, resilient retainer
75 means connected with the bottom portion of said
body adapted to embracingly engage said bulb to
75

hold said body against displacement therefrom, said retainer means comprising a pair of circular wire loop members respectively affixed to diametrically opposite points of said body bottom portion to normally lie flatly folded thereagainst but capable of being flexed and spread apart to receive said bulb therebetween.

7. A vapor emanator comprising, a closed hollow annular body to contain a vaporizable fume emitting substance and adapted to be supported by and around an electric light bulb, means formed in connection with said body adapted to provide external up-flow air passages between said body and the side of a bulb to which it is operatively applied and ingoing air admission ports communicating with the interior of said body above the level of fume emitting substance contained therein, and said body having vent means in its closed top portion.

20 8. A vapor emanator comprising, a hollow annular upwardly open bottom section to contain a vaporizable fume emitting substance and adapted to be supported by and around an electric light bulb, a cover section to close the open top of said bottom section, said cover section having vent means leading outwardly from the bottom section interior, circumferentially spaced concavo-convex ribs disposed to project from the inner walls of said bottom section, thereby providing external air flow passages intermediate the latter and said bulb, and said ribs having air intake openings on their undersides leading into the interior of said bottom section above the level of fume emitting substance contained therein, the upper curved sides of said ribs being adapted to serve as deflector means to direct ingoing air into the bottom section interior for the purposes described.

30 9. A vapor emanator comprising, a hollow annular upwardly open bottom section to contain a vaporizable fume emitting substance and adapted to be supported by and around an electric light bulb, a cover section to close the open top of said bottom section, said cover section hav-

ing vent means leading outwardly from the bottom section interior, circumferentially spaced concavo-convex ribs disposed to project from the inner walls of said bottom section, thereby providing external air flow passages intermediate the latter and said bulb, said ribs having air intake openings on their undersides leading into the interior of said bottom section above the level of fume emitting substance contained therein, the upper curved sides of said ribs being adapted to serve as deflector means to direct ingoing air into the bottom section interior for the purposes described, and resilient retainer means connected with said bottom section adapted to embracingly engage said bulb to hold the emanator against displacement therefrom.

35 10. A vapor emanator comprising, a hollow annular upwardly open bottom section to contain a vaporizable fume emitting substance and adapted to be supported by and around an electric light bulb, a cover section to close the open top of said bottom section, said cover section having vent means leading outwardly from the bottom section interior, circumferentially spaced concavo-convex ribs disposed to project from the inner walls of said bottom section, thereby providing external air flow passages intermediate the latter and said bulb, said ribs having air intake openings on their undersides leading into the interior of said bottom section, the upper curved sides of said ribs being adapted to serve as deflector means to direct ingoing air into the bottom section interior for the purposes described, resilient retainer means connected with said bottom section adapted to embracingly engage said bulb to hold the emanator against displacement therefrom, said retainer means comprising a pair of circular spring wire loop members respectively affixed externally to diametrically opposite points of said bottom section to normally lie flatly folded thereagainst but capable of being flexed and spread apart to receive said bulb therebetween.

RUSSELL B. KINGMAN.
